Howard E. Barlow

Attorney

UNITED STATES PATENT OFFICE.

FREDERICK I. JOHNSON, OF WARREN, RHODE ISLAND, ASSIGNOR TO MARY W. JOHNSON, OF WARREN, RHODE ISLAND.

CONDUIT END FITTING.

Application filed August 27, 1920. Serial No. 406,837.

To all whom it may concern:

Be it known that I, FREDERICK I. JOHNSON, a citizen of the United States, residing at Warren, in the county of Bristol and 5 State of Rhode Island, have invented certain new and useful Improvements in Conduit End Fittings, of which the following is a specification.

This invention relates to an end-fitting 10 for an electrical conduit of the class adapted to close the end thereof, to protect the electric wires leading therefrom and permit the fitting to be screwed onto the end of a threaded conduit or pipe without twisting 15 the wires leading therethrough.

The nature and advantages of the invention will be better understood when the following detail description is taken in connection with the accompanying drawings, 20 the invention residing in the combination and arrangement of parts as claimed.

In the drawings forming part of this specification, like numerals of reference indicate similar parts in the several views and 25 wherein:

Figure 1 is a sectional side elevation of my improved device showing one means of securing the nut in the neck portion thereof.

Figure 2 is a side elevation of the device 30 illustrated in Figure 1, showing another means of securing the nut member in the neck portion thereof.

Figure 3 is a bottom view of the device.

Figure 4 is a side elevation of the fitting 35 mounted on the end of an electric conduit.

My improved device is preferably constructed of thin sheet stock having a neck or nut-receiving portion 10 in the form of a cup with a bottom portion 11 punched 40 out leaving an inwardly-extending bottom flange 12 and having an outwardly extending annular flange 13 at its outer end. A separate nut member 14 is formed of a thicker stock than this casing portion, 45 which nut member is provided with a peripheral polygonal contour, and the neck portion of the casing may be swaged by a simple process to engage these faces of the nut to prevent the same from rotating 50 therein, and as illustrated in Figure 1, finger members 15 may be formed from the stock of the neck and bent over the inner face of the nut to secure it in position therein.

55 The usual insulating head member 16 is

ordinarily provided with a lower edge flange 17 and to connect this nut-engaging neck member to the flange portion of this head, I have provided a band member 18 which has inwardly-turned upper and lower 60 edges 19 and 20 the lower edge engaging the flange 13 of the neck member while the upper edge 20 is turned inwardly over the flange member 17 of the head member thereby providing a simple and effective 65 means for connecting the neck member to the head member so that one may freely rotate relative to the other.

In some instances instead of providing the inwardly-turned fingers 15, illustrated 70 in Figure 1, for securing the nut in the neck member I swage that portion 21 of the neck member above the nut, over the edge thereof, to securely bind the nut in position in this end fitting. 75

By my improved construction this end fitting comprises but four pieces and the neck portion may be held to turn freely relative to the band portion, if desired, and the head 16 may also be loosely mounted 80 in the band portion 18 to turn freely therein whereby the head member may be held stationary relative to the other parts while the neck portion is being screwed onto the threaded end of the conduit 22 without 85 twisting the electrical wires 23 passing through the conduit and out through the openings in the end of the head.

This device is extremely simple and practical in construction and may be formed 90 of very thin stock and a separate nut may be employed of thicker stock only where such thickness is required. Then again by this construction the incasing of the nut member 14 strengthens the same, permitting 95 its walls to be made thinner than would otherwise be the case.

The foregoing description is directed solely towards the construction illustrated, but I desire it to be understood that I reserve the privilege of resorting to all the mechanical changes to which the device is susceptible, the invention being defined and limited only by the terms of the appended claims. 100

I claim:

1. A conduit and fitting comprising an insulating head member, a nut-engaging neck member having an integral outturned flange and a band member having its edges 110

turned inwardly to connect said flange portion to said head whereby one may rotate relative to the other, a nut in said member, and means in said neck member for firmly embracing said nut.

2. A conduit end fitting comprising an insulating head having a flange, a nut-carrying neck member having an integral out-turned flange upon which said head rests, 10 and a band having one edge turned over said head flange and its other edge turned over said neck flange loosely connecting them together.

3. A conduit end fitting comprising an insulating head having a flange, a nut-carrying neck member having an integral out-turned flange upon which said head rests, 15 and a band having one edge turned over

said head flange and its other edge turned over said neck flange loosely connecting them together, a nut in said neck member, and means in said neck member for rigidly embracing said nut.

4. A conduit end fitting comprising an insulating head, a metal band engaging said head, its lower edge forming an inturned flange, a neck member having an outturned flange loosely engaging said inturned flange to permit relative rotation of said parts, a nut, said neck portion embracing the external contour of said nut and inturned integral fingers in said neck for locking said nut therein.

In testimony whereof I affix my signature.

FREDERICK L. JOHNSON.
